UNITED STATES PATENT OFFICE.

HARRY ELMER GUNN, OF CHICAGO, ILLINOIS.

STOVE-BOARD.

1,283,504.

Specification of Letters Patent. Patented Nov. 5, 1918.

Application filed April 20, 1917. Serial No. 163,366.

To all whom it may concern:

Be it known that I, HARRY ELMER GUNN, a citizen of the United States, residing at Chicago, in the county of Cook and State of Illinois, have invented new and useful Improvements in Stove-Boards, of which the following is a full, clear, and exact description.

My invention relates to stove-boards, and particularly to that class of stove-boards the lining or bodies of which are made of wood and have the top and edges thereof covered with sheet metal.

The lining or bodies of stove-boards of this kind are generally square and have been made of two layers each consisting of thin strips of wood corresponding in length to the length of the stove-board and arranged side by side with their side edges in contact throughout this length. The top layer is placed upon the lower layer so that the strips thereof are arranged crosswise to those of the lower layer, and then the two layers are nailed together with tacks, and the edges trimmed and the corners rounded preparatory to covering the same. The covering consists of sheet tin of a shape corresponding to that of the body over which it is placed in such manner that its downwardly flanged edges lap past and inclose the edges of the lining or body and are then bent under and stamped by a suitable press against the under margins of the same.

This construction has been in use for years, but while it has been extensively used, it is objectionable because, owing to the heat and the flimsy character of the wood used in its construction, the lining or body buckles, twists and shrinks and causes the tin covering to buckle and the under turned edges thereof to work loose, thus causing the separation of said lining or body and falling apart when moved. The great objection to making stove-boards in any other manner than as above described, is due to the necessity of using lumber for the lining or body which, even when thoroughly kiln dried, will buckle and twist and shrink, whether the wood is solid or arranged in layers, and to the great expense of the means employed to prevent this happening.

The object of my invention is to construct a stove-board of wood which will not warp or twist or shrink and which is particularly adapted for use in this connection because

it is practically inflammable, and is to construct and secure the cover thereto in such manner that the attachment of the latter thereto will be permanent and will not buckle or work loose. This I accomplish in the manner hereinafter fully described, and as particularly pointed out in the claims.

In the drawings:

Figure 1 is a plan view of the underside of a stove-board embodying my invention.

Fig. 2 is a transverse section therethrough taken on dotted line 2—2, Fig. 1.

Fig. 3 is a longitudinal section taken on dotted line 3—3, Fig. 1.

Referring to the drawings, A, A, represent a series of redwood strips or planks, that, preferably, correspond in length and width and are about five eighths of an inch in thickness. These strips are provided with longitudinal tenons *a* projecting from one longitudinal edge thereof, and with corresponding longitudinal grooves in the opposite edge thereof. I prefer to make these tenons and grooves slightly dovetail and to apply glue to the contacting edges of the strips and join the strips together by inserting the tenon of one strip endwise into the groove in the edge of the next strip.

The outer edges *c*, *c*, of the outer border strips C, C, of this series of strips A is, preferably, planed so as to remove the tenon of the one border strip and the groove of the other. The end edges of the strips A terminate in the same transverse plane and are provided with transverse alining dovetail grooves *d*, *d*, and a border or cross-strip D of the same kind of wood, which has a longitudinal dovetail tenon *e* on its inner edge joined and glued to the end edges of the lengthwise strips A. When the body or lining of the stove-board, as thus constructed, has thoroughly dried its edges are trimmed to give it the desired rectangular shape and its corners rounded about as shown in the drawings.

The border-strips C and D are provided on their undersides with longitudinal grooves E, E, that are parallel to and near their outer edges, and the inner side-walls of these grooves are inclined at a suitable angle and their outer side-walls are perpendicular to the underside of the stove-board. These grooves E may extend the entire length of the border strips, or may terminate short of the ends thereof, and while I prefer to make the shape of their transverse

contours as just described they may be shaped differently and accomplish the purpose for which they are intended.

When the lining or body of the stove-board has been completed, as hereinbefore explained, its upper surface and edges are covered by sheet tin or other suitable material. The superficial area of this cover F is the same as that of the finished lining or body, and when it is placed upon said lining its edges are flanged downward and then bent under the edges of the lining. The extent of the projection of the portion of these flanges engaging the corners of the stove-board is less than that of the portions between said corners, which latter portions project about twice as far so as to provide lips g, g. When the top and edges of the lining has been incased in said cover in the manner stated, the stove-boards are turned upside down and the lips are forced by machinery or otherwise into grooves E of the border strips and thoroughly and permanently clench the cover in place.

What I claim as new is:

1. A stove-board comprising a lining and cover therefor; said lining consisting of a series of corresponding parallel redwood

strips each having an undercut groove in one longitudinal edge and a corresponding undercut tenon in the other through the medium of which they are joined together, and cross-strips of the same material the inner edges of which are provided with an undercut tenon which enters transverse grooves in the ends of said series of strips and joins the same together, and said cover consisting of sheet metal applied to the upper surface of said lining and having its edges flanged downward against and inclosing the edges of said lining.

2. A stove board lining, comprising a series of co-extensive wooden strips in longitudinal edge contact and joined to each other by an undercut tongue and groove connection in each instance, and a pair of end strips of wood each traversing the ends of the first named strips at one side of the lining and joined to them by an undercut tongue and groove connection.

In witness whereof I have hereunto set my hand this 11th day of April, 1917.

HARRY ELMER GUNN.
